UNITED STATES PATENT OFFICE.

JOHN PABICH, OF MOUNT CARMEL, PENNSYLVANIA.

SHIP-PROTECTOR.

1,347,120.

Specification of Letters Patent. Patented July 20, 1920.

Application filed January 9, 1919. Serial No. 270,308.

To all whom it may concern:

Be it known that I, JOHN PABICH, a citizen of the United States, residing at Mount Carmel, in the county of Northumberland, State of Pennsylvania, have invented certain new and useful Improvements in Ship-Protectors; and I do hereby declare the following to be a full, clear, and exact description of the invention, such as will enable others skilled in the art to which it appertains to make and use the same.

This invention relates to a ship protector, and more particularly to the class of torpedo guards for ships.

15. The primary object of the invention is, the provision of a guard of this character, wherein the same is suspended at the side of a ship, it being understood of course that a plurality of these guards are employed 20 along opposite sides of the ship below the water level to arrest the torpedo in its flight and prevent the explosion from damaging the ship.

Another object of the invention is, the 25 provision of a guard of this character, wherein the same can be readily raised or lowered above or below the water level, and in the event that the guard is damaged by a torpedo or mine on the explosion thereof, or 30 the contact of the same therewith, repairs can be made with despatch or a new guard placed in its stead.

A further object of the invention is the 35 provision of a guard of this character which is simple in construction, readily and easily applied to and removed from the ship, easily raised and lowered, and inexpensive to manufacture and install.

With these and other objects in view, the 40 invention consists in the features of construction, combination and arrangement of parts as will be hereinafter fully described, illustrated in the accompanying drawing and pointed out in the claims hereunto appended.

In the accompanying drawing:

Figure 1 is a fragmentary top plan view of the device applied to a ship's hull.

Fig. 2 is a fragmentary vertical sectional view showing the device in operative position.

Fig. 3 is an elevation of the guard.

Fig. 4 is a fragmentary sectional view on the line 4—4 of Fig. 2, with the parts enlarged.

Fig. 5 is a fragmentary vertical sectional

view showing the guard in raised position, and

Fig. 6 is a fragmentary vertical sectional view on the line 6—6 of Fig. 1, as viewed at 60 right angles to Fig. 4.

Similar reference characters indicate corresponding parts throughout the several views in the drawing.

Referring to the drawing in detail, A, designates generally a portion of a vessel or ship and outside of the same spaced therefrom longitudinally throughout the length thereof is arranged a plurality of torpedo guards, only one of the same being illustrated and hereinafter fully described.

The guard comprises a shield body 10 preferably made from reticulated or a steel wire mesh section, although in lieu a solid steel plate may be employed, and this body 75 is supported upon a back frame including spaced longitudinally disposed bars 11 and transverse bars 12, which latter have connected thereto double leaf hinges 13 for the swinging movement of the body 10, the 80 hinges being also connected to a swinging bracket or support hereinafter fully described.

The swinging bracket or support comprises a pair of arms 14 arranged in spaced 85 parallel relation to each other and are formed with right angular upturned outer ends 15 to which are fastened the hinges 13, the arms 14 being held in parallel relation through the medium of spaced parallel 90 braces 14' disposed across and connecting the same. Connected to the inner ends of the arms 14 are hinges 17 which have fixed thereto tongues 18 for detachably mounting on the hull A of the ship or vessel, as will 95 now be described. Mounted exteriorly of the hull A is a pair of spaced cleats or loops 19 in which are detachably received the tongues 18 for the detachable mounting of the supporting frame which constitutes a 100 spacer for the body 10 of the guard on the lowering of the latter to operative position away from the hull A of the ship or vessel.

On the under side of the arms 14 of the supporting frame are right angular stops 105 20, which are adapted to engage the loops 19 to limit the downward swinging movement of the supporting frame and to sustain it when in lowered position in a substantially horizontal plane.

Connected with the upper longitudinal bar 11 of the frame for the body 10 and also

connected with the hull A, of the ship or vessel are socket members 21 in which are loosely engaged the ball terminals 22 of a brace rod 23 which is adapted to be disposed substantially parallel with the supporting frame when lowered to a horizontal plane and will prevent the swinging of the body 10 from its upright position outwardly spaced from the side of the hull A, of the 10 ship or vessel and will rigidly hold the body when struck by a torpedo or mine so as to intercept the flight of the torpedo and the striking of the mine against the hull of the vessel or any damage to the latter from the 15 explosion of the torpedo or mine.

The body 10 of the guard can be readily raised to elevated position in any suitable manner when the guard is not in use as the supporting frame can be vertically swung 20 for elevating the body to bring it into inoperative position or to lower the body so that it will be supported below the water level for guarding the hull of the vessel, the arms 14 of the supporting frame being of a 25 length to space the body 10 of the guard from the side of the vessel to prevent the torpedo or mine from striking the ship or vessel and prevent the explosion thereof from doing harm to the hull.

Should damage occur to the body 10 or to the supporting frame the tongues 18 can be removed from the loops 19 to permit the guard to be swung upward toward and taken aboard the vessel for convenience in 30 repairing the guard and on detaching the brace, a new guard can be placed in its stead.

The brace rods 23 are employed one at 40 either end of the respective frames or guard sections and extend at obtuse angles or obliquely therefrom beyond the frames or guard sections, thereby effectively bracing the latter from moving to either side. By reason of disposing the rods 23 in a horizontal plane parallel to the plane of the arms 14 and obliquely, both are permitted to swing upwardly on their pivots or centers while at the same time being maintained in 45 parallel relation and without binding, as well as maintaining the guard sections parallel or substantially parallel to the hull, as is particularly shown in Figs. 2 and 5 of the drawings. As means to raise the guard as shown in Fig. 5, suitable connections are extended to the deck of the ship 50 which shall be readily accessible, and as

illustrated, rods 15' are provided, being hinged to the ends 15 and designed to be anchored in any suitable manner to the hull in order to brace the guard sections against 60 upward movement, when in use, if desired. The hinge pintles 17' are also elongated, as is particularly shown in Fig. 4, to prevent the leaf hinges and tongues from dropping 65 too far into the loops.

What is claimed is:

1. In a ship protector, the combination with a shield section and its supporting frame, and a pair of loops adapted to be attached to the hull; of a pair of arms hinged 70 at their outer ends to said frame, a hinge having one leaf connected with the inner end of each arm, a tongue attached to the other leaf and adapted to be dropped into said loop, a right angular stop having one 75 leaf secured beneath the arm and the other engaging said loop when the arm stands horizontal, rods pivotally connecting the frame and hull, and means for raising the frame.

2. In a ship protector, the combination with a shield section and its supporting frame, and a pair of loops adapted to be attached to the hull; of a pair of arms adapted to be hingedly connected at their inner 80 ends to the loops, their outer ends being bent upward at right angles, hinges connecting the up-bent portions with said frame, rods hinged to the up-bent portions and leading inboard, and braces pivotally 85 connecting the frame and hull at other points.

3. In a ship protector, the combination with the substantially upright wall of a hull, and a substantially upright shield 95 body; of loops attached to said wall, arms in one plane between the wall and body, hinges at their inner ends having tongues for engaging said loops, right angular stops adjacent these hinges, the outer ends of the arms 100 being turned upward at right angles, hinges connecting the upturned ends with the body, brace rods connecting the latter with the hull in a higher plane than said arms, ball-and-socket joints at the extremities of said 105 rods, and means for raising the frame.

In testimony whereof, I affix my signature, in the presence of two witnesses.

JOHN PABICH.
